(57) **CLAIM**

The ornamental design for a fuel cap as shown and described.

DESCRIPTION

FIG. 1 is a perspective view of a fuel cap showing my new design;

FIG. 2 is a front view thereof;

FIG. 3 is a rear view thereof;

FIG. 4 is a first side view thereof;

FIG. 5 is a second side view thereof;

FIG. 6 is a bottom view thereof;

FIG. 7 is a top view thereof;

FIG. 8 is a top perspective view thereof with a handle, bottom portion and key not shown; and,

FIG. 9 is a bottom view with the handle, bottom portion and key not shown.

The broken lines in the figures are included for the purpose of illustrating portions of a fuel cap and form no part of the claimed design.

1 Claim, 9 Drawing Sheets
